(57) **CLAIM**

The ornamental design for a shotblasting apparatus, as shown and described.

DESCRIPTION

FIG. 1 is front, first side/top perspective view showing the new design;

FIG. 2 is front side view thereof;

FIG. 3 is a back view thereof;

FIG. 4 is a second side view thereof;

FIG. 5 is a first side view thereof;

FIG. 6 is a top view thereof;

FIG. 7 is a bottom view thereof; and,

FIG. 8 is a front perspective view shown in an alternate configuration of use.

The broken lines in the figures depict portions of the shotblasting apparatus which form no part of the claimed design.
